CLAIM

The ornamental design for a storage device with slide, as shown and described.

DESCRIPTION

FIG. 1 is a front isometric view of the storage device with slide in an operational configuration;

FIG. 2 is a rear view of the storage device with slide in the operational configuration;

FIG. 3 is a top view of the storage device with slide in the operational configuration, the bottom being a mirror image thereof;

FIG. 4 is a front view of the storage device with slide in the operational configuration;

FIG. 5 is a left-side view of the storage device with slide in the operational configuration;

FIG. 6 is a right-side view of the storage device with slide in the operational configuration;

FIG. 7 is a front isometric view of the storage device with slide in a non-operational configuration;

FIG. 8 is a rear view of the storage device with slide in the non-operational configuration;

FIG. 9 is a top view of the storage device with slide in the non-operational configuration, the bottom being a mirror image thereof;

FIG. 10 is a front view of the storage device with slide in the non-operational configuration;

FIG. 11 is a left-side view of the storage device with slide in the non-operational configuration; and,

FIG. 12 is a right-side view of the storage device with slide in the non-operational configuration.

The broken-line showing of a Universal Serial Bus (USB) male connector in the various figures is for environmental purposes only and forms no part of the claimed design.
